ILLUMINATED NOVELTY

Filed July 13, 1931

INVENTOR.

Ernest W. Herring

UNITED STATES PATENT OFFICE

ERNEST W. HERRING, OF MAYWOOD, CALIFORNIA

ILLUMINATED NOVELTY

Application filed July 13, 1931. Serial No. 550,318.

This invention relates to improvements in illumination novelties designed more particularly to produce such ornaments as tree ornaments and the like.

One of the objects of this invention is to provide a simple, efficient and inexpensive device whereby a single length of conductor wire is designed to be folded back upon itself a number of turns for the purpose of providing branches of a tree as well as supports for electric lamps and the like.

Another important object of this invention is to provide a tree ornament of such a shape and form that all the integral parts thereof including the trunk, branches as well as the pedestal will be designed to support electric lamps for illumination purposes.

A further object of this invention is to provide a tree ornament so designed, shaped and constructed that it can be manufactured very cheaply and inexpensively and will be capable of giving shape and body to a tree trunk as well as branches.

Another important object of the present invention is to produce a tree ornament by employing a length of conductor wire made stout enough to be shaped into the trunk and branches of a tree novelty, the same wires being connected to an electrical circuit so that current may be conducted thru the wires to the electric lamps secured upon the wires.

A still further object of this invention is to provide a tree illuminated novelty the various parts of which consist of upright wire stems with angularly disposed branches formed thereon, upon which electric lights or lamps are placed or mounted at the tip ends of the branches.

With the above and other objects in view my invention consists in the combination, arrangement and details of construction disclosed in the specification, and then more particularly pointed out in the appended claims.

In the drawing, wherein similar reference characters designate similar parts throughout the respective views,

Figure 1 is a perspective view of my invention,

Figure 2 is a vertical sectional elevation

of the pedestal showing my invention applied operatively therein,

Figure 3 is a top plan view of my invention, and

Figure 4 is a detail fragmental view of a single lamp with its under wire support.

In the drawing, which is merely illustrative of my invention 10 designates a pedestal of any suitable stout material having a base 11. The pedestal is made hollow there thru and so also is the broad base of the pedestal 11. My invention of lamp and lamp mounting consists of a single length of electrically conductive wire made into a number of successive integral folds as will now be fully described.

The wire cable 14 contains in its wrapping the terminals 15, 16 of an electrical circuit, each wire being separate from the other but arranged to have their folds disposed in contacting manner as will now be explained. Each terminal 15, or 16 is practically shaped and arranged in the same manner. Thus terminal 15 has a vertical fold 15a passing upwardly in the pedestal, and is bent angularly and laterally above the pedestal to provide the branch wire 15b, which is electrically connected to a small electric lamp 35, and thence extends the parallel contacting wire terminal 15, having an angular wire 17a overlying wire 15b, and then being bent in upright form and

extending downwardly back into the pedestal 10, where the same wire is folded back at 17c so as to contact the vertical branch fold 18, which projects above wires 15b, 17a, and is formed with an angular fold wire 18a having the rightangular upstanding wire terminal 15c, connected to the electric lamp 18b', from which extends the downward contacting vertical wire 18b having a bent angular wire 18a overlying wire 18b, from whence the vertical wire 19 extends downwardly in contacting relation with wire 18 into the pedestal, where

another and upright parallel fold is formed in wire terminal 15, as an integral part thereof, this new fold wire 20 extending upwardly from the lower end of the pedestal 10 in contacting relation with the upstanding wire fold 19, but extending higher than the last

named wire to provide another angular branch wire having a rightangular upright terminal 23, to which an electric lamp 35 is also connected shown covered by the tissue paper of a definite color 34 from whence extends in return manner the parallel contacting upright wire 23a, bent at right angles at 23b, and then bent again in upright manner and extended downwardly in contact with the upright wire 19, until it extends back into the pedestal where it joins another fold as at 24a, whence another upright wire stem 24 extends upwardly in contacting relation with the previous upright wire, and this upright wire 24a is caused to extend unbent to the uppermost end of the lamp post where it joins another paper-covered lamp or electric light 35 of any approved design. Here another and separate wire is joined to the last-named lamp, altho the same wire may be continued to produce the other side of the illuminated tree ornament.

The upright wire 25 leaves the uppermost electric light or lamp and extends down into the pedestal contacting the lower portion of the next adjacent upright wire therein, and now a new fold is produced in wire 25 and the vertical upshoot wire 26 extends up to the point where it is bent angularly at 26a in alignment with wire 23b, and this wire 26a is in turn bent upwardly at 26b, parallel with wires 23, 23a, where it joins the supported electric lamp 35, from which extends downwardly wire 27b to contact wire 26b, which wire 27b makes a rightangular turn as at 27a, where the wire is again bent to provide the upstanding wire 27 which extends downwardly to contact upstanding wire 25, and to enter the pedestal 10 again, where another fold is produced in the same wire so now the upstanding wire 28 contacts the next adjacent upright wire stem in pedestal 10, and extends above the pedestal where it is provided with a rightangular bend 28a terminating in an upstanding wire terminal 28b, to which a lamp is connected, from which extends the upright downwardly disposed wire stem 29b, contacting wire 28b, and bent again to produce the angular wire 29a, contacting wire 28a; the two wires 28a, 29a are disposed in alignment with wires 18a and the wire contacting the same. The wire 29a is bent again at right angles to produce the upstanding wire stem 29, which contacts wire 28, and which extends downwardly into the pedestal and is there provided with an integral wire stem 30, extending upwardly in the pedestal where it is bent to provide an upstanding angular wire arm 30a, having a terminal carrying another electric lamp 35, from which the wire 31a extends backwardly in contact with wire 30a, and thence wire 31a extends back into the pedestal to contact wire 30a therein, and another fold is produced on wire 31a, designated 32, and this wire extends upwardly

and angularly as at 32a, where its upstanding terminal carries lamp 35 and thence the wire 33a runs back in parallel contacting relation with wire 32a, and is bent back into upright position and made to return back into the pedestal 10, where it becomes the final terminal 16 which is included in the cable 14 which runs to a generator or battery of approved design.

The electric lamps thus far described is designed to be covered with colored tissue paper or the like 34 to enhance the attractiveness of the illumination. It will be seen that the branches on opposite sides of the tree are caused to shoot out horizontally and in opposite direction; also that the higher the branches extend the shorter these branches become, and finally the uppermost branches will be of the shortest length. The lamps may extend, on opposite sides of the trunk of the tree in parallel formation if desired, but may be shaped in an entirely different manner. Thus in Figure 1 it will be seen that the lowermost branches extend divergently upwards, while in Figure 3 it is seen that the branches extend out radially of the trunk. The trunk of the tree is made strong as many upright wires are arranged in contacting relation to provide it. It will thus be seen that many different colored light effects can be produced by means of shaping the single wire or two wires with their folds to support lamps and the like. I do not mean to confine myself to the exact details of construction save as pointed out in the appended claims.

What I desire to claim and secure by Letters Patent is:—

1. A device of the kind described consisting of a pedestal, and a length of wire made into a plurality of folds, each of the folds consisting of twisted parts, some portions of the wire being arranged in folded contacting upright position, with respect to which the folds extend angularly as branches of a tree, lamps fused upon the branch-like folds of the device, said wires being included in an electric circuit for furnishing current to the lamps.

2. A device of the kind described consisting of a pedestal having an interior bore, said pedestal having a base support, a length of wire bent and doubled upon itself to provide a plurality of contacting wires each produced from folds of the wire, the doubled portions of the wire being disposed in a vertical arrangement to provide a main trunk of a tree, with angularly-extending arms arranged as branches of a tree in superposed relation, certain portions of the wire passing into the interior bore of the pedestal, and being connected in an electrical circuit, and a series of lamps secured upon the arms of the tree.

3. A device of the kind described consisting of a pedestal having an interior bore, and also having a broad base, a single length of

conductor wire bent and folded upon itself to provide a plurality of doubled-up contacting portions, certain of said doubled contacting portions of the wire being disposed in upright position to provide a trunk of a tree, other doubled integral portions of the wire being disposed at an angle to the main trunk to provide tree branches, a series of lamps fused upon the ends of the branches of the tree, there being separate terminals of the wire connected in an electrical circuit.

4. A device of the kind described consisting of a pedestal having an interior bore, and also having a broad base opening out at its bottom, a single length of wire folded and doubled upon itself with the folded parts in firm contact with each other, certain parts of the folded portions of the wire being disposed in upright position, and other parts being folded in angular position, lighting devices mounted upon the angular parts of the wire folded portions designed for electric illumination, certain other portions of the wire passing thru the bore of the pedestal into the base, where same are connected in an electrical circuit.

5. A device of the kind described consisting of a hollow pedestal having a base support, an electrical cord passing into the base support and projecting into the pedestal, and consisting of a pair of conductor wires, each conductor wire being folded upon itself at a number of points to provide folded portions having contacting parts, a plurality of the contacting folded parts of the separate wires being disposed in upright position and contacting relationship to provide the trunk of a tree, another plurality of contacting folded wires disposed angularly of the trunk and carrying lighted lamps at their outer ends to which electrical current is fed by means of the pair of conductor wires.

6. As a new article of manufacture, the combination of an upright having an interior bore and a flat base having an opening, a pair of wires, one wire being folded a number of turns upon itself and arranged in upright position, the other wire also being folded a number of turns upon itself and arranged in upright position, the upright portions of both wires being contacted one against another to provide a solid standard for a lamp, and integral portions of both wires being extended angularly of the solid portion to provide tree branches, electric lamps attached upon the mentioned branches to which current is conducted by said wires, paper ornaments enclosing the lamps, and a cord, the wires passing thru the base hole to be connected to said cord.

7. As a new article of manufacture, the combination of a hollow pedestal having a broad base formed with a hole therein, a pair of electrical conductor wires, both wires having a series of parallel folded portions with

their parts contacting, all of said parallel folded portions being tightly bunched together and arranged in upright position with their lower parts projecting into the pedestal, the several parallel portions of the wires being arranged to have their terminals bent angularly outwards from upright position in a vertically graduated manner to simulate tree branches, said wires projecting thru the base hole to be connected thence to an electrical circuit, electric lamps secured upon the ends of the tree branches for tree illumination, and paper ornaments wrapped around the lamps, said ornaments having varying colors.

In witness whereof he has hereunder set his hand this 20th day of June, 1931.
